DISPOSABLE SYRINGE

George P. Kempel, Cuyahoga Falls, Ohio

Application May 15, 1951, Serial No. 226,442

21 Claims. (Cl. 128—224)

1

This invention relates to syringes and, in particular, to a douche bag capable of easy fabrication from low-cost materials, so that it may be discarded after a single use.

Douche bags have become a matter of necessity, according to modern standards of feminine hygiene, to such extent that they are generally considered a necessary implement even during travel. To this end, manufacturers have striven to make the bags in such manner that they may be easily stored in a minimum of space. Despite such facilitation, however, and for various reasons, it quite frequently happens that a party finds herself embarrassed for need of one of these items when away from her domicile. In such a case, it is not a welcome solution to purchase an extra bag of the type capable of long-term use. According to the present invention, there is provided a syringe which can be sold at low cost and may, therefore, be discarded after a single use. Also, being composed largely of thin, plastic material, it may be folded into a small, compact, inconspicuous bundle, so that one or several packages may be included in a traveling bag, or even a hand bag, without seriously compromising the storage capacity available for other articles.

It is, therefore, an object of the invention to provide a syringe which is low in cost, so as to be disposable after a single use. A further object is to provide a syringe which may be consolidated into a comparatively small volume for carrying purposes and easy merchandising.

A still further object is to provide for a syringe having easy manipulation whereby filling is facilitated and positive closing of the filler opening is easily accomplished, permitting evacuation of the bag by manual pressure thereon.

These and other objects, which will be apparent, are attained by the invention, a preferred form of which is described in the accompanying specification and illustrated in the drawings, in which:

Fig. 1 is an elevational view of the syringe in a condition preparatory to filling, showing in broken lines the nozzle as presented for assembly, and with the path of assembly of the nozzle indicated by a series of arrows.

Fig. 2 is a top plan view of Fig. 1.

Fig. 3 is a sectional view taken on the line 3—3 of Fig. 1.

Fig. 4 is a sectional view taken on the line 4—4 of Fig. 2.

Fig. 5 is a sectional view taken on the line 5—5 of Fig. 1.

Fig. 6 is a fragmentary view showing the filler

2

tube rolled up and secured to prevent back flow of liquid.

Fig. 7 is a sectional view taken on the line 7—7 of Fig. 6, and

Fig. 8 is a plan view of the rubber band used as a sealing means.

Referring to the drawings by characters of reference, there is shown a bag 10 composed of thin sheeting of a tough plastic, such as one of the vinyl plastics. Conveniently, the bag is formed from a single layer blank folded at its middle to form the bottom 11 and heat-sealed along the sides 12 and 13.

The blank is formed with inner recesses 14 which, when heat-sealed together along their boundaries 16, 17 and 18, define, respectively, a filler tube 19, an outlet tube 21 for receiving a spray nozzle 22, and a top portion of the bag. Nozzle 22, which has the usual ports 23, is composed of soft rubber or the like and has a flared bottom 24 so that liquid under pressure will urge the nozzle against the tube 21 and help defeat the tendency of liquid to pass between the tube and the nozzle. Preferably, the bag will be filleted, as at 26 and 27, to accommodate the flared bottom of the nozzle. In assembling the nozzle with the bag, as shown in the broken line representation, it is introduced, outer end foremost, into larger tube 19 and then worked into position in tube 21 as shown by the arrows. The nozzle may be cemented in place in tube 21, although this is not entirely essential.

For filling purposes, the mouth of tube 19 is reinforced by means of a relatively rigid, plastic, elliptical ring 28, as best seen in Fig. 4, the ring being sealed in place by cement, or by heat sealing if the ring and bag are composed of mutually compatible material.

After filling the bag, the tube 19 is sealed against outflow of liquid by folding it back upon itself in one or more folds. Folding is commenced by rotating the ring 28 about its major axis. It will be seen that the oblate form of ring is of assistance in such folding. However, folding may be accomplished using other shapes of rings, such as circular or square for instance. In Fig. 7, the folding is shown in a condition resulting from one and one-half turns of the ring 28. This provides sufficient sealing of the tube to prevent outflow of water, but the tube 19 may be of sufficient length that at least one more turn may be accomplished.

For greatest ease of manipulation of the syringe in ejecting the contents, it is desirable that a locking means be provided for the tube

19 in its folded condition. Any simple clip, or a rubber band, may be adequate for this purpose. However, as a widely used commercial product, the syringe should be complete and fool-proof. A preferred form of clasp, as shown in the drawings, comprises a special form of rubber band in cooperative relation with a pair of knobs 29 on the ring 28 having neck portions 31 to receive the rubber band and prevent too easy removal thereof. The rubber band, which may be cut by conventional methods from specially extruded stock, has two outer loops 32 and a small central loop 33, the latter being of a size to ensure retention on one of the knobs 29. With the central loop thus mounted, and the tube 19 in folded condition, the outer loops 32 of the band are grasped by end tabs 35 and stretched across opposite sides of the ring 28 so that each may be looped around the opposite knob. This prevents unfolding. As sold, the bag will contain a water-soluble antiseptic substance 34 and, therefore, the package will be shipped with tube 19 in the folded and secured position shown in Fig. 6. Sale of the package with the tube thus folded is of further advantage in that it clearly instructs the user as to the manner of closing and securing the filler opening.

With the nozzle 22 and powder 34 in place, and tube 19 sealed off, the nozzle is folded upon the bag to prevent outflow of the powder. Further folding of the article to provide a minimum of volume for placement in an outer container of wax paper or the like may be accomplished in any convenient manner. The volume of the article when folded will not be much greater than the combined volume of the nozzle 22, ring 28 and powder 34, the actual volume of the plastic bag itself being small.

While a certain preferred form of the invention has been shown and described, the same is not strictly limited thereby, since certain changes in the exact shape, form and arrangement, for instance, of the various parts, may be resorted to without departing from the spirit or scope of the invention as defined in the appended claims.

What is claimed is:

1. A disposable syringe comprising a flat bag of heat-sealable plastic sheeting, a first extension on said bag forming a filler opening, a reinforcing ring secured at the mouth of said opening, said first extension being of sufficient length to allow for folding thereof by turning said ring, a second extension on said bag, and a spray nozzle located in said second extension.

2. A disposable syringe comprising a flat bag of heat-sealable plastic sheeting, a first extension on said bag forming a filler opening, a reinforcing ring secured at the mouth of said opening, said first extension being of sufficient length to allow for folding thereof by turning said ring, a second extension on said bag, and a spray nozzle located in said second extension, said filler opening having a greater area than the opening of said second extension and said nozzle having an inner, enlarged portion adapted to pass through said filler opening but to be retained by said second extension.

3. A disposable syringe comprising a flat bag of heat-sealable plastic sheeting, a first extension on said bag forming a filler opening, a reinforcing ring secured at the mouth of said opening, said first extension being of sufficient length to allow for folding thereof by turning said ring, a second extension on said bag, and a spray nozzle located in said second extension, said ring being oblate and having outer knobs located in line with the long dimension of the ring, for anchoring a rubber band or the like to hold said first extension in folded condition.

5 nozzle located in said second extension, said filler opening having a greater area than the opening of said second extension and said nozzle having an inner, flared portion adapted to pass through said filler opening but to be retained by said second extension.

10 4. A disposable syringe comprising a flat bag of heat-sealable plastic sheeting, a first extension on said bag forming a filler opening, a reinforcing ring secured at the mouth of said opening, said first extension being of sufficient length to allow for folding thereof by turning said ring, a second extension on said bag, and a spray nozzle located in said second extension, said filler opening having a greater area than the opening of said second extension and said nozzle having an inner, flared portion adapted to pass through said filler opening but to be retained by said second extension, and said second extension having a flared portion adapted to mate with the said flared portion of said nozzle.

15 5. A disposable syringe comprising a flat bag of heat-sealable plastic sheeting, a first extension on said bag forming a filler opening, a reinforcing ring secured at the mouth of said opening, said first extension being of sufficient length to allow for folding thereof by turning said ring, a second extension on said bag, and a spray nozzle located in said second extension, said ring being oblate with its longer dimension parallel to the plane of the bag in flat condition whereby to facilitate folding of said first extension.

20 6. A disposable syringe comprising a flat bag of plastic sheeting, a first extension on said bag forming a filler opening, a reinforcing ring secured at the mouth of said opening, said first extension being of sufficient length to allow for folding thereof by turning said ring, a second extension on said bag, a spray nozzle located in said second extension, and clamp means carried by said ring for holding said first extension in folded condition.

25 7. A disposable syringe comprising a flat bag of plastic sheeting, a first extension on said bag forming a filler opening, a reinforcing ring secured at the mouth of said opening, said first extension being of sufficient length to allow for folding thereof by turning said ring, a second extension on said bag, and a spray nozzle located in said second extension, said ring having outer lugs adapted to anchor a rubber band or the like for holding said first extension in folded condition.

30 8. A disposable syringe comprising a flat bag of plastic sheeting, a first extension on said bag forming a filler opening, a reinforcing ring secured at the mouth of said opening, said first extension being of sufficient length to allow for folding thereof by turning said ring, a second extension on said bag, and a spray nozzle located in said second extension, said extensions being located on the same end of the bag.

35 9. A disposable syringe comprising a flat bag of plastic sheeting, a first extension on said bag forming a filler opening, a reinforcing ring secured at the mouth of said opening, said first extension being of sufficient length to allow for folding thereof by turning said ring, a second extension on said bag, and a spray nozzle located in said second extension, said ring being oblate and having outer knobs located in line with the long dimension of the ring, for anchoring a rubber band or the like to hold said first extension in folded condition.

10. A disposable syringe comprising a flat bag of heat-sealable plastic sheeting, a first extension on said bag forming a filler opening, a reinforcing ring secured at the mouth of said opening, said first extension being of sufficient length to allow for folding thereof by turning said ring longitudinally of said extension to close said opening, a second extension on said bag, and a spray nozzle of soft, rubber-like material located in said second extension.

11. A disposable syringe comprising a flat bag of plastic sheeting, a first extension on said bag forming a filler opening, a reinforcing ring secured at the mouth of said opening, said first extension being of sufficient length to allow for folding thereof by turning said ring, a second extension on said bag, a spray nozzle located in said second extension, and releasable means to hold said first extension in folded condition.

12. The combination of an air and water impervious cover, a disposable syringe in folded condition inside said cover, and an antiseptic powder contained in said syringe, said syringe comprising a flat bag of relatively thin, disposable water impervious sheet material, a first extension on said bag forming a filler opening, a reinforcing ring secured at the mouth of said opening, said ring also constituting means for folding said extension longitudinally upon itself to close said opening, releasable means holding said first extension in folded condition, a second extension on said bag, and a spray nozzle located in said second extension, said nozzle being turned back upon said bag and being held turned back by said cover.

13. A disposable syringe comprising a flat bag of plastic sheeting, a first extension on said bag forming a filler opening, a reinforcing ring secured at the mouth of said opening, said first extension being of sufficient length to allow for folding thereof by turning said ring, a second extension on said bag, a spray nozzle located in said second extension, said ring having a pair of outer lugs, and a rubber band having a small loop carried on one of said lugs, and a larger loop adapted to engage the other of said lugs.

14. A disposable syringe comprising a flat bag of plastic sheeting, a first extension on said bag forming a filler opening, a reinforcing ring secured at the mouth of said opening, said first extension being of sufficient length to allow for folding thereof by turning said ring, a second extension on said bag, a spray nozzle located in said second extension, said ring having a pair of oppositely disposed outer lugs, and a rubber band having a small loop carried on one of said lugs, and a larger loop adapted to engage the other of said lugs.

15. A disposable syringe comprising a flat bag of plastic sheeting, a first extension on said bag forming a filler opening, a reinforcing ring secured at the mouth of said opening, said first extension being of sufficient length to allow for folding thereof by turning said ring, a second extension on said bag, a spray nozzle located in said second extension, said ring having a pair of oppositely disposed outer lugs, and a rubber band having a small loop carried on one of said lugs, and a larger loop adapted to engage the other of

said lugs, said ring being oblate and said lugs being arranged in the line of the major axis of said ring.

16. A disposable syringe comprising a flat bag of plastic sheeting, a first extension on said bag forming a filler opening, a reinforcing ring secured at the mouth of said opening, said first extension being of sufficient length to allow for folding thereof by turning said ring, a second extension on said bag, a spray nozzle located in said second extension, said ring having a pair of outer lugs, and a rubber band having a small intermediate loop carried on one of said lugs, and two larger, outer loops, each adapted to engage the other of said lugs.

17. A syringe comprising a bag having a tubular filler extension, a reinforcing ring of material which is rigid relative to the material of the bag, and means carried by said ring and adapted to clamp said extension in folded condition.

18. A syringe comprising a bag having a tubular filler extension, a reinforcing ring of material which is rigid relative to the material of the bag, a pair of opposed outer lugs on said ring, and a resilient, clamping band anchored on one of said lugs and adapted to also engage the other of said lugs.

19. A syringe comprising a bag having a tubular filler extension, an oblate reinforcing ring of material which is rigid relative to the material of the bag, a pair of opposed outer lugs on said ring, and a resilient, clamping band anchored on one of said lugs and adapted to also engage the other of said lugs.

20. A syringe comprising a flat bag of relatively thin disposable sheet material, a first extension on said bag forming a filler opening, a reinforcing ring secured at the mouth of said opening, said ring also constituting means for folding said extension longitudinally upon itself to close said opening, means engageable with said ring for keeping said opening closed, a second extension on said bag, and a spray nozzle slidably received in said second extension.

21. A syringe comprising a flat bag of relatively thin, disposable water impervious sheet material, a first extension on said bag forming a filler opening, a reinforcing ring secured at the mouth of said opening, said ring also constituting means for folding said first extension upon itself to close said opening, releasable means holding said first extension in folded condition, a second extension on said bag substantially parallel with said first extension and on the same side of the bag as said first extension, and a spray nozzle held in anti-leaking position in said second extension.
